H. T. BARNWELL,
CURTAIN ROD BRACKET.
APPLICATION FILED APR. 27, 1921.

1,405,891.

Patented Feb. 7, 1922.

Inventor:
Harry T. Barnwell,

By Cashman, Bryant & Darby
Atty's.

UNITED STATES PATENT OFFICE.

HARRY T. BARNWELL, OF OGDENSBURG, NEW YORK, ASSIGNOR TO THE NEWELL MFG. CO. INC., OF OGDENSBURG, NEW YORK, A CORPORATION OF MAINE.

CURTAIN-ROD BRACKET.

1,405,891.

Specification of Letters Patent. Patented Feb. 7, 1922.

Application filed April 27, 1921. Serial No. 464,807.

To all whom it may concern:

Be it known that I, HARRY T. BARNWELL, a citizen of the United States, residing at Ogdensburg, in the county of St. Lawrence 5 and State of New York, have invented new and useful Improvements in Curtain-Rod Brackets, of which the following is a specification.

The present invention relates to brackets 10 for curtain rods, and particularly to that type of bracket formed of sheet metal, and designed to support hollow curtain rods by means of suitable projections which engage the tubular end of the rod.

15 In order that the invention may be clear to those skilled in the art, I have shown in the accompanying drawings physical embodiments of my development, and in said drawings:

20 Fig. 1 is a plan view of a cut out and died up blank.

Fig. 2 is a view of the blank in Fig. 1 with its heads bent to proper position for rod support.

25 Fig. 3 is a view in side elevation of a bracket attached to a window casing (conventionally shown) with a portion of a curtain rod supported by the bracket.

Fig. 4 is a view in plan of a slightly different form of blank.

Fig. 5 is a view in elevation of the blank shown in Fig. 4, with the supporting heads brought to proper position.

Fig. 6 is a view similar to the construction 35 shown in Figs. 1 and 2, applied to a different type of bracket.

Fig. 7 is a view of the blank shown in Fig. 6, with the rod supporting heads bent to proper position.

40 Referring to the drawings by numbers, like numbers indicating like parts in the several views, 10 indicates the base plate of the blank having suitable apertures 11 by which the blank is fastened to the wall.

45 The blank is substantially cruciform as shown in Fig. 1, the base plate 10 being cut away on each side to a substantially hour-glass contour, so as to give a narrowed body section centrally thereof and from this narrowed section extend lateral heads 12.

50 The heads 12 are died or stamped up into substantially elliptical contour in plan and give them a substantially half round and cupped form in cross-section as shown in Fig. 2, and 55 they are connected to the narrow central

section of the base plate 10 by the reduced unstamped necks 13.

This blank shown in Fig. 1 is preferably formed by one operation of stamping out and dieing, being cut from a metal sheet 60 of any suitable composition and gauge.

In this condition, the heads 12 will be bent up to the position shown in Fig. 2 by any suitable bending mechanism, the narrowed necks 13 which, it will be observed, are not 65 stamped or died up, providing an easily bendable section, which, with the ductile metal used, will permit the heads 12 to be readily bent to their final position as shown in Fig. 2.

70 The heads 12 projected from the narrowed central section of the base plate 10 will be brought into relatively close relation by a single bend of the necks 13 so that they will lie close together as indicated in Fig. 2, and 75 in a proper position to receive the telescoping hollow curtain rod 14, as illustrated in Fig. 3. The length of the rounded heads 12 and their contour is such that they will give 80 an extended and firm bearing for the rod 14, and the resiliency of the heads 12 is such that they will grip the rod 14, and prevent any looseness, the rounded ends of the died up heads 12 permitting the hollow rod 14 to be easily telescoped over these spring 85 heads.

In the form shown in Figs. 4 and 5, the blank is of the same general form as that just described, having the base plate 15 and the laterally disposed heads 16, the base 90 plate being notched or cut back on either side of the heads as shown, so as to give a narrowed central portion. The heads 16, instead of being joined by a reduced neck portion as in the other views, are simply 95 died up to give the rounded sections from a point slightly removed from the junction of the arms with the narrowed central portion of the base plate and the heads 16 half rounded completely to their ends, instead of 100 having those ends rounded up as in the form shown in Figs. 1 to 3, inclusive.

The blank shown in Fig. 4 will be brought to the condition shown in Fig. 5 by bending up the heads 16, substantially along the 105 dotted lines shown in Fig. 4, and being provided at this point with a small section of flat undied metal so that the bending operation is comparatively easy. By reason of the heads 16 being joined to the nar- 110

rowed central portion of the base plate 15, they will, as shown in Fig. 5, be brought into close relation so as to permit small tubular rods to be used, and yet in this form 5 as in the form shown in Figs. 1 to 3, a base plate of the necessary width to give a firm seating on the window casing or other wall surface is provided.

In Figs. 6 and 7, I have shown the application of my invention to a slightly different form of bracket. In this form, as appears from Fig. 6, the blank will be cut and died up from suitable sheet metal but one of the heads 17 will be cut and died 10 out within the area of the base plate 18, both heads 17 being joined by the narrow necks 19 to the base plate.

The supporting heads 17 will then be bent up at their narrow neck portions to the position shown in Fig. 7, where they lie in the same close relation as do the supporting heads in the other forms, and in proper position to receive and hold a small tubular curtain rod. The base plate 18 will preferably be bent along the dotted lines shown 20 in Fig. 6, to provide the flange 20 shown in Fig. 7, which stands at right angles to the rest of the base plate, thereby providing an angular base with the perforations for the 25 fastening means in both the base plate proper 18, and the base flange 20.

Brackets constructed in accordance with this invention, may be very cheaply and rapidly produced, the cutting and dieing 30 processes being performed simultaneously on the sheet to form the blanks and the provision of the bending necks or areas between the died up heads and the base plates permits the ready bending of the heads to their 35 final position, and additionally the narrowing, or cutting in of the base plates cen-

trally to bring the bending lines for the supporting heads close together, ensures the close relation of the supporting heads to receive the tubular rods without sacrificing 40 proper width of the base plate.

I claim:

1. A curtain rod bracket comprising a base plate having an integral narrow section between its ends, rod engaging heads 50 disposed laterally with respect to said base plate, and reduced neck portions of bendable material connecting said heads and said narrow section.

2. A curtain rod bracket comprising a 55 base-plate having its side portions cut away to form a narrow, central section; stamped-up heads, curved in cross-section, projecting laterally from said narrow, central section; and flat, reduced neck-portions of bendable 60 material connecting said heads and central sections.

3. A curtain rod bracket comprising a flat base-plate having a central section of reduced width; stamped up, rod-engaging 65 heads of substantially elliptical form extending laterally from said reduced section; and flat, narrow neck-portions of bendable material connecting said heads and base plate. 70

4. A curtain rod bracket comprising a base-plate of substantially hour-glass contour; stamped-up heads, cupped in cross-section and of substantially elliptical shape, projecting laterally from the narrow body 75 section of said base-plate; and flat narrow necks of bendable material connecting said heads with said narrow body section.

In testimony whereof I have hereunto set my hand.

HARRY T. BARNWELL.
